UNITED STATES PATENT OFFICE

EDWARD W. KRISE, OF WILKES-BARRE, PENNSYLVANIA

AUTOMATIC BURNER

Application filed March 7, 1930. Serial No. 434,135.

The object of this invention is the provision of an automatic fuel saving and combustion increasing apparatus for boilers, furnaces and other heating plants in which the draft to the plant is retarded by partly closing the chimney dampers and wherein a forced draft is created in the ashpit for forcing air into the combustion chamber to mix with the gases of combustion as they are generated so that the latter will ignite and burn and such burning gases, by the draft in the chimney stack will result in a proper combustion and a considerable saving in fuel consumption.

A further object is the provision of a fuel saving and combustion increasing apparatus in which fans are operated by a motor, the outlet of both of such fans being valve controlled, and the outlet of one of the fans being directed into the ashpit, the outlet for the second fan having a flexible pipe connected thereto which is directed to the fuel door for the combustion chamber of the heating plant and which has fixed on its end a spray nozzle, the chamber for the last mentioned fan providing a receptacle for a quantity of water whereby the air sprayed into the combustion chamber is humidified to aid in the consumption of the fuel in such chamber and further wherein the device is suspended on springs attached to a suitable frame so as to eliminate as much as possible any noise made by the vibration of the motor when in operation.

For a full and comprehensive understanding of the improvement, reference is to be had to the drawings which accompany and form part of this application.

In the drawings:

Figure 1 is an end elevation of the improvement in operative position, the heating plant being in section.

Figure 2 is a view of the improvement looking toward the second end thereof.

Figure 3 is a top plan view with parts broken away and parts in section.

Figure 4 is a transverse sectional view approximately on the line 4-4 of Figure 3.

Figure 5 is a side elevation with parts in section of the nozzle pipe.

In Figure 1 of the drawings, the numeral 1 designates the casing of a furnace or like heating plant, 2 the ash pit, 3 the grate, 4 the door for the ashpit and 5 the door for the combustion chamber.

In carrying out my invention I arrange on the supporting floor for the heating plant 1, at a suitable distance therefrom a motor 6 which is preferably electrically driven. The shaft 7 for the motor is extended through the opposite sides of the casing for the motor. On one end of the shaft 7 there is fixed a fan which is preferably electrically driven. The housing is of cast iron or pressed steel and is fastened stationary to the motor casing by a plate 10 which has on its outer face equidistantly spaced concaved lugs 11 which are extended over the bearing 12 for one end of the shaft 7 and arranged so as to receive through openings therein bolts 13 that project from the side of the motor casing, the said bolts being engaged by suitable nuts. The outer end of the housing 9 has a square opening therein surrounded by a flange 14 and which opening provides an air intake. The housing at the front thereof is provided with a round opening surrounded by an outlet pipe 15. The passage through this pipe is controlled by a pivotally supported disc valve 16 that has on its shaft binding means 17 for holding the valve in proper angular position to regulate the outflow of air through the housing. The pipe 15 has a flexible joint connection 18 with a pipe 19 that passes through an opening in the door 4 and which pipe enters the ash pit 2. When the motor is in operation the fan is revolved to draw air into the housing and to force such air through the outlet pipes 15 and 19 into the ashpit 2 to create a forced draft into the ash pit and for delivering a proper amount of such forced draft through the grate 3 for generating gas into the combustion chamber 20 of the furnace or plant. The amount of air thus delivered is, of course, regulated by the adjustment of the disc valve 16 as heretofore stated.

On the opposite or second end of the motor casing there is another fan 21 enclosed in a housing 22 that is smaller in proportion to

the housing 9. The housing 22 is made of cast iron or pressed steel and is bolted to the motor casing 6 through the medium of spaced concaved lugs 23 in the same manner as the housing 9 is connected to the said motor casing. The lugs 23, however, are not connected to a plate similar to the plate 10 but are integrally formed with the side of the housing 22.

10 The outer end of the housing 22 is open to permit of the arrangement of the fan 21 on the end of the motor shaft 7, but this end is thereafter closed by a plate 24 which is bolted to the housing 22. The plate 24 has a square opening therethrough surrounded by an outwardly directed flange 25 and this opening provides an air inlet to the housing 22. The housing 22 has a deepened bottom portion which affords a well for a quantity 20 of water 26 and the level of the water is arranged directly in a line with the lower blade of the fan 21 or slightly therebelow. The air circulated by the fan 21 is directed from the housing 22 through an outlet pipe 27 and the 25 passage through this pipe is controlled by a disc valve or damper 28. The pivot for the valve has an offset end in the nature of a handle through which is screwed a binding element 29 to contact with the pipe 27 and 30 for regulating the adjustment of the valve or damper 28.

Connected to the end of the outlet spout or pipe 27 there is one end of a flexible tube or pipe 30, the second end of the said pipe 30 being connected to a short pipe 31 that is directed through a suitable opening in the door 5. A coupling 32 is arranged upon the pipe 31 to close the opening in the door 5 through which the said pipe passes. The end of the 40 short pipe 31 has screwed thereon a U-coupling 33 in whose end there is screwed a nozzle pipe 34. The nozzle pipe is provided with a series of apertures 35, and the outer end of the pipe 34 is closed by a cap nut 36.

45 The nozzle 35 is arranged in the combustion chamber 20 of the heating plant as disclosed by Figure 1 of the drawings. The turning of the fan will compress the air in the housing 22 and force the same through the 50 apertures in the nozzle pipe 34 so that the combustion chamber will be subjected to a complete spray of such air. The water in the housing 22 will moisten this air so that a humidified spray of air is delivered into the 55 combustion chamber and this air mixing with the gas generated from the coal will mix with such gas and thereby produce a complete combustion. It is to be understood that the damper smoke outlet pipe for the heating plant 60 is closed and it will be obvious that gases which naturally escape through such pipe or stack will be burned with the result that with the improvement a proper combustion and a considerable saving in coal consumption is obtained. It is, of course, to be understood that

the damper of the smoke outlet pipe is of the usual construction, that is, the same is provided with openings for the passage of noxious gases and such gases are drawn out of the outlet pipe by the draft created therein, which draft is accelerated by the draft in the ash box and in the fire box created by the fans of the improvement.

70 In order to eliminate as far as possible noise created by the motor and the fans in the 75 operation thereof, and which noises would be prominently apparent were the motor and fan arranged upon a stationary support, the motor and fan housings are fixed in an inner open substantially rectangular metal frame 37, 80 and the frame 37 is arranged in an outer open substantially rectangular frame 38. Between the inner corners of the frame 38 and the outer corners of the frame 37 there are secured the ends of strong coiled springs 39; and these 85 springs flexibly support the inner motor and fan housing supporting frame 37. The outer frame is reinforced by suitable angle braces 40. In order that all of the gases contained 90 in the coal may be consumed, the coal is always built in the rear of a small sized furnace or boiler. The thicker or heavier the coal at the sides sloping down to the center or at the fire door the more gases derived from the coal. It is, of course, not the coal, after being heated to a red heat that furnishes the 95 heat to the building in which the device is installed but it is the gases forced up through the coal from the burning coal all over the firebox that furnishes heat for the burner. 100 By slowly exposing the coal through the center or front, the coal naturally burns until the next firing, and all of the hot coals are raked to the center of the furnace. Then after the furnace is again filled with fresh coal it may 105 be left for hours at a time. It is to be noted that there is always left red hot coals at the center of the fire box or at the end thereof. These coals produce what may be termed a 110 pilot light. The housing on the end of the motor shaft causes the gases to be heated and burned, and by having this fan separate and independent from the fan that furnishes air for the ashpit a complete control over the air 115 that goes into the fire box is afforded. Therefore, it is essential that air in the fire box be controlled by a fan motor other than the fan that furnishes air to the ash pit. A sufficient amount of air at all times is required in the fire box at the same time that moistened air 120 is delivered to the ashpit.

125 It is believed that the construction and operation of my improved automatic fuel saving and combustion increasing apparatus for heating plants will be understood and appreciated so that further detailed description will not be required but obviously I do not wish to be restricted to the precise details herein set forth and, therefore, hold myself entitled to make such changes therefrom 130

as fairly fall within the scope of what I claim.

Having described the invention, I claim:

1. A fuel saving and combustion increasing apparatus for heating plants in which the smoke outlet of such plant is provided with a partially open damper, comprising a motor, a fan driven thereby having a pipe connection with the ash pit of the heating plant for creating a forced draft therein, a second fan also driven by said motor and having a pipe connection with the combustion chamber of the plant and provided with an apertured nozzle which is arranged in the combustion chamber, a housing containing water and the water in the housing being acted upon by the last mentioned fan.

2. A fuel saving and combustion increasing apparatus for heating plants in which the smoke outlet of such plant is partly closed by a damper, comprising a motor, a fan driven thereby having a pipe connection with the ashpit of the heating plant for creating a forced draft therein, a second fan also driven by said motor and having a pipe connection with the combustion chamber of the plant and provided with an apertured nozzle which is arranged in the combustion chamber, a housing containing water which is contacted by the blades of the last named fan at the revolution thereof, a hand operated damper controlling the passage through the pipe and yieldable supporting means for the motor and fan.

3. A fuel saving and combustion increasing apparatus for heating plants having ash pits and in which the smoke outlet for the plant is partly closed, comprising a motor having a drive shaft extending from the ends thereof, housings fixed to but spaced from the sides of the motor casing, said housings having air inlet openings in their outer sides, a fan in each housing fixed on the ends of the motor shaft, a valve controlled air outlet for each housing, a pipe having a flexible connection with one of such outlets and received in the ashpit of the heating plant, the second housing having a deepened bottom providing a water receptacle, a flexible pipe connected to the outlet of the said housing, a short pipe directed through the fuel door of the combustion chamber of the heating plant and to which the flexible pipe is connected, an angularly arranged apertured nozzle pipe coupled to the short pipe and arranged in the combustion chamber and said nozzle pipe having its outer end closed.

In testimony whereof I affix my signature.
EDWARD W. KRISE.
